UNITED STATES PATENT OFFICE.

JOHN RANDOLPH SEES, OF NEW YORK, N. Y., ASSIGNOR TO WM. F. WEAVER, OF PHILADELPHIA, PENNSYLVANIA.

IMPROVEMENT IN FEED-WATER HEATERS.

Specification forming part of Letters Patent No. 42,538, dated April 26, 1864.

To all whom it may concern:

Be it known that I, JOHN RANDOLPH SEES, of the city of New York, in the State of New York, have invented a certain new and useful Improvement for Heating the Feed-Water of Steam-Boilers; and I do hereby declare the following to be a full, clear, and exact description thereof, reference being had to the accompanying drawings, and to the marks and letters thereon.

My improvement, though more especially designed for marine boilers, may be used in land, or stationary, or portable boilers. The drawings, forming part of this specification, show this improvement attached to a horizontal tubular boiler, Figure 1 of the drawings being a side view of the smoke-box and a small portion of the boiler, the heater being indicated by red lines, and Fig. 2 being a front view of the smoke-box and the heater contained therein. In both of these figures, where like parts are shown, like marks and letters are used to indicate the parts. Within the smoke-box *a* is placed a hollow diaphragm, *b*, made of corrugated plates, which are so secured to each other as to render the diaphragm water-tight. The interior of the diaphragm at the bottom, by a pipe, *c*, is in communication with the valve-chamber *d* of the feed-pump, and at the top in communication by another pipe, *e*, with the water-space of the boiler. From the upper end of the valve-chamber *d* a circulating-pipe, *f*, passes to the water-space of the boiler. The pipe from the feed-pump is attached to the lower end of the valve-chamber, and hence when the pump is in action the track of the water is through the valve-chamber into the pipe *c* and into the interior of the diaphragm, and from the diaphragm through the pipe *e* into the water-space of the boiler. When the pump is not

in action, there will be a circulation of water through the diaphragm by the falling down of the valve on its lower seat, and the communication being through the pipe *f*, valve-chamber *d*, pipe *c*, the interior of the diaphragm, and pipe *e*. On the one side the diaphragm is supported by the pipes and the other side by rods, the bottom supports being trunnions, which are screwed or flanged in, as occasion may require. The diaphragm is inclined, as shown by Fig. 1, and the way I determine the set is to take the united area of the flues and allow just that area between the top of the diaphragm and the flue-sheet of the boiler, and then, both areas being the same, the draft is not affected, and there is no occasion ever after to alter the diaphragm. At any convenient point in the bottom of the diaphragm-heater a hole may be made, into which can be screwed a gage-cock, so that at any moment the cock may be opened and any mud or sediment in the heater may be blown out. By making the diaphragm-heater of corrugated plates more heating-surface is obtained than when made of plain plates, and the corrugations stay the sheets or plates, so that bolts or stay-rods will not be required. This heater may easily be so hung or sustained in the smoke-box as to readily allow access to the tubes or flues for cleaning or breeching.

What I claim as my invention, and desire to secure by Letters Patent, is—

The corrugated diaphragm feed-water heater, attached in the manner and for the purposes herein set forth.

This specification signed this 30th day of September, 1863.

JOHN RANDOLPH SEES.
